US00D543333S

(12) **United States Design Patent** (10) **Patent No.:** **US D543,333 S**
(45) **Date of Patent:** **** May 22, 2007**

(54) **ELECTRONIC PART CONVEYOR TABLE**

(75) Inventor: **Tomoyuki Kojima**, Tokyo-To (JP)

(73) Assignee: **Tokyo Weld Co., Ltd.**, Tokyo-to (JP)

(**) Term: **14 Years**

(21) Appl. No.: **29/218,479**

(22) Filed: **Dec. 3, 2004**

(30) **Foreign Application Priority Data**

Jun. 21, 2004 (JP) 2004-018489

(51) **LOC (8) Cl.** **12-05**

(52) **U.S. Cl.** **D34/29**

(58) **Field of Classification Search** D34/29, D34/35; 198/834, 833, 835; 474/155, 156, 474/157, 164; D8/499, 20, 70

See application file for complete search history.

(57) **CLAIM**

The ornamental design for an electronic part conveyor table, as shown and described.

DESCRIPTION

FIG. 1 is a front perspective view of an electronic part conveyor table showing my novel design;

FIG. 2 is a rear perspective view thereof;

FIG. 3 is a front elevational view thereof;

FIG. 4 is a rear elevational view thereof;

FIG. 5 is a top plan view thereof; the opposite side view being the same;

FIG. 6 is a cross-sectional view taken along line 6—6 in FIG. 3; and,

FIG. 7 is a right side elevational view thereof, the opposite side view being the same.

1 Claim, 2 Drawing Sheets

FIG. 7

FIG. 1

FIG. 2

FIG. 3

FIG. 4

FIG. 5

FIG. 6
